APPARATUS FOR EJECTING FROM BLANKS
BEING FED TO CAN BODY MAKING MA-
CHINES AND THE LIKE, DOUBLE-FED AND
OVER-THICK BLANKS

Peter Kruse, New York, N. Y.

Application February 29, 1944, Serial No. 524,378

9 Claims. (Cl. 209—88)

1

This invention relates to apparatus for ejecting from blanks being fed to can body making machines and the like, double blanks and overthick blanks, and provides improvements therein.

The invention provides an apparatus of the character described which is simple in construction and reliable in operation, and functions to prevent double blanks, or over-thick blanks, entering a can body making machine or like apparatus, and thereby breaking parts of, or jamming, such apparatus, and causing long delays in the operation thereof. Modern body making machinery operates at high speed, and the present invention provides an apparatus which, while operating at like speed, does not throw the ejected blanks about but handles them in a safe and orderly manner.

An embodiment of the invention is illustrated in the accompanying drawings, wherein

Fig. 1 is a view of said embodiment, partly in plan and partly in section, looking down from the line 1—1, Fig. 2;

Fig. 2 is a vertical sectional view on the line 2—2, Fig. 1;

Fig. 3 is an enlarged sectional view on the line 3—3, Fig. 2;

Fig. 4 is an enlarged detail view of parts shown at the upper left-hand part of Fig. 1 of the drawings, in a different operative position.

The invention may receive other embodiments than that illustrated and specifically described.

Referring to said drawings, numeral 10 designates a table on which blanks are fed. The blanks may be fed from a hopper 12, as is usual, by any well-known means. The blanks are carried forward from the hopper (or starting position) by suitable means. Advantageously the means has a reciprocatory motion, with a slow start and stop in the forward direction. Feed-bars 15, 16, reciprocating in guides 18, 19 in table 10 may be used. The feed-bars carry sets of feed-fingers 21, 22, 23, the sets 22, 23 being depressible so as to pass under blanks strung out on the feed-table 10 on the return stroke of the feed-bars. The feed-bars 15, 16, may be reciprocated by a crank-driven lever 25 pivotally connected to a link 27, which latter is connected to a cross-piece 29 to which the bars 15, 16, are attached. A center rest 31 on the table beyond the hopper and hold-down rails 33 over the blanks are provided, which serve to control the blank while it is being fed, especially at high speed. The hold-down rails 33 may be supported over the blanks by a bracket 35 attached to a beam 37 which arches the table 10, the rails having pins 40 which fit in holes in

2

the bracket 35. Springs 41 may be provided for pressing the rails down onto table part 31.

A shelf 45 may be provided on table 10, on which ejected blanks are received and stacked.

Means are provided for feeding a blank on table 10 to a can body maker (a part of which is illustrated at the right-hand side of Fig. 2), or other apparatus utilizing the blank. This means may comprise a feed-slide 50 which is reciprocated at right angles to the motion of the feed-bars 15, 16. The feed slide 50 may be reciprocated by suitable means, as by a cam 54 on a driven shaft 56, and a lever 58 which is connected to the slide 50 through a clutch 60. The clutch may comprise a block 62, connected to a vertically movable lifter 64, and having a fork or notch 65 for receiving the end or a part of reciprocatory lever 58. The block 62 also has a foot 66 under which the end of lever 58 rides when the clutch-block 62 is disengaged from the lever 58, and which insures re-engagement of the lever with the notch 65 in the block. The clutch-block 62 is connected to lifter 64 in a suitable manner, as by a pin 67 passing through a slot 68 having a length equal to the reciprocation imparted to feed slide 50.

The lifter 64 of clutch 60 is advantageously operated by a solenoid 70, as by being connected to the armature 71 thereof by a pin.

30 The solenoid is energized to disconnect the clutch 60 from lever 58 when a double blank or too thick a blank is fed along feed-table 10. For this purpose a feeler-finger 75 may be provided, which finger contacts an adjusting screw 76 carried by a lever 77 pivoted on bracket 35 and cooperating with an arm 79 of a switch 80 controlling an electric circuit to solenoid 70. The feeler-finger 75 is adjusted to a height above the feed-table 10 equal to just about the thickness 40 of a normal blank, and the arrangement is such that a slight rise of finger 75 above this height is sufficient to actuate switch-arm 79 to close the circuit to solenoid 70.

Single and normal blanks do not pass forward 45 on table 10 beyond the fed-position under the feeler-finger 75, and stops 83 may be provided for accurately positioning the blanks at this position at right angles to the line of feed, so that they may be fed true from this position to the can body maker, or other apparatus utilizing the blank. The stops 83 are vertically movably supported, as by the blocks 84 on brackets fastened to beam 37, and springs 86 may be provided for normally pressing them down below the line of 55 feed of the blanks. Projections 88, in the form

of rollers, are provided for lifting the stops 83 slightly above the line of feed, so that double blanks or overthick blanks may be fed onto shelf 45. The shelf 45 may be slightly elevated above the line of feed of the blanks, so that the rollers 88 may pass under the blanks on shelf 45, and the latter may be provided with a bevelled front side 90 on which blanks may ride onto the shelf.

Operation

On each reciprocation of the feed bars 15, 16, blanks are fed along table 10 from a hopper 12. The blanks pass under feeler-finger 75, and if a blank is a normal blank, normal operation of the apparatus ensues. As the feed-bars start back, after positioning the blank against stops 83, the reciprocatory feed-slide 50 engages a side of the blank and advances it crosswise of table 10 toward a body-maker or other apparatus utilizing the blanks, where it is gripped and its movements controlled by parts of the latter apparatus.

However, if two blanks are simultaneously fed from hopper 12, or an overthick blank, when they come under feeler-finger 75, the feeler-finger will be lifted and will act through lever 77 to operate switch-arm 79 to close the electric circuit to solenoid 70 and thereby energize it to lift its armature 71. The armature will raise lifter 64 and the latter will lift clutch-block 62, and thereby disengage the reciprocatory lever 58 from the notch 65 in the clutch-block, so that the feed-slide 50 remains stationary while lever 58 can continue to reciprocate beneath the block 62 and the foot 66 thereon. This occurs before the feed-slide 50 has engaged the double blanks, and thereby the entry of double blanks, or overthick blanks, into the can body maker, is prevented, together with interruptions of operation of the latter apparatus which might be caused by such double or overthick blanks. On the next forward reciprocation of feed-bars 15, 16, an overthick or double blank beneath feeler-finger 75 will be carried forward onto shelf 45. The leading edge of the blank will ride up beveled edge 90 onto said shelf, and, when another blank is on shelf 45, ensuing blanks will stack up under it. The underside stacking of the blanks on shelf 45 will prevent blanks fed out from under the hold-downs 33 from flying about and constituting a potential source of injury to persons and apparatus. At the time the feed bars 15, 16, act to move the double blanks forward from beneath feeler-finger 75, the stops 83 are lifted above the line of feed by the roller-projections 88 on the feed-bars. The stops will be held lifted by the rollers 88 long enough for the leading edges of the double blanks to be advanced beneath them, after which the stops are held up by the blanks until they pass onto shelf 45, whereupon they again drop into position across the line of feed.

When the space on table 10 beneath feeler-finger 75 is clear, or occupied by a normal blank, finger 75 acting through lever 77, breaks the circuit to solenoid 70. This allows armature 71 to drop, and with it the lifter 64. Clutch-block 62 will drop, so that the end of reciprocatory lever 58 engages the notch 65 when said end rides off foot 66 to a position beneath notch 65. With lever 58 engaged with clutch-block 62, feed-slide 50 resumes its movement in timed relation to the feed-bars 15, 16. The slot 68 in lifter 64 constitutes a loose horizontal connection which permits clutch-block 62 to reciprocate with relation to lifter 64.

What is claimed is:

1. Apparatus for ejecting from a series of blanks being fed to can body making machines and the like, double and over-thick blanks, comprising means (A) for feeding blanks in a line, means (B) for feeding a blank laterally from said line, to be received by a machine utilizing the blanks; said means (B) comprising a reciprocatory part for contacting a blank at one side, and means for reciprocating said reciprocatory part; and means for stopping the motion of said reciprocatory part responsive to means for detecting the presence of more than one blank or an over-thick blank in the line of feed of feeding means (A), said stopping means comprising a clutch in the means for reciprocating said reciprocatory part; said detecting means comprising a feeler displaceable by double blanks and over-thick blanks in the line of feed of feeding means A, said clutch being remote from said detecting means, and electrical means actuated by said feeler upon a movement of the latter for disengaging said remotely located clutch and thereby stopping the movement of said reciprocatory part of the feeding means (B), the construction and operation being such that when double-fed blanks and over-thick blanks are in feeding position for feeding means B, feeding means B is rendered inoperative and the blanks are ejected by feeding means A.

2. Apparatus according to claim 1, wherein said feeding means A further comprises reciprocatory feed-bars, and further comprising positive stops in the line of feed of blanks fed by feeding means A at the position thereof in line with feeding means B, and means on said reciprocatory feed-bars of feeding means A for raising said stops above the level of blanks, at the initiation of each feed movement of the feed bars of feeding means A, so that when the action of feeding means B is stopped and blanks remain at the position of feeding means B, succeeding movement of the feed bars of feeding means A advances edge portions of the blanks, left in position by feeding means B, beneath the uplifted stops and thereby enables the blanks to be slid beneath said stops and be ejected.

3. Apparatus according to claim 1, wherein said feeding means A further comprises reciprocatory feed bars, and further comprising positive stops in the line of feed of blanks fed by feeding means A at the position thereof in line with feeding means B, and means on said reciprocatory feed bars of feeding means A for raising said stops above the level of blanks, at the initiation of each feed movement of the feed-bars of feeding means A, so that when the action of feeding means B is stopped and blanks remain at the position of feeding means B, succeeding movement of the feed bars of feeding means A advantages edge portions of the blanks, left in position by feeding means B, beneath the uplifted stops and thereby enables the blanks to be slid beneath said stops and be ejected; a shaft beyond feeding means B for receiving blanks ejected by feeding means A, and fixed means also beyond feeding means B for guiding blanks being ejected to a position beneath other blanks stacked on said shelf.

4. Apparatus according to claim 1, further comprising a shelf beyond feeding means B for receiving blanks ejected by feeding means A, and a fixed means also beyond feeding means B for guiding blanks being ejected to a position beneath other blanks stacked on said shelf.

5. Apparatus according to claim 1, wherein

said electrical means for stopping the action of feeding means B further comprises a solenoid having an armature, a connection between said armature and clutch, and a switch, actuated from said feeler, in an electric circuit with said solenoid.

6. Apparatus for ejecting from a series of blanks being fed to can body making machines and the like, double and overthick blanks, comprising means (A) for feeding blanks in a line, reciprocatory means (B) for feeding a blank laterally from said line, to be received by a machine utilizing the blanks, a feeler displaceable by doubled-fed and overthick blanks fed by means A, said feeding means B comprising a slide, a continuously reciprocated part, a clutch-part on said slide movable to and from engagement with said continuously reciprocated part remote from said feeler, and electrical means operated from said feeler for moving said remotely located clutch-part to a position of disengagement, the construction and operation being such that when doubled-fed blanks and overthick blanks are in feeding position for feeding means B, feeding means B is rendered inoperative and the blanks are ejected by feeding means A.

7. Apparatus according to claim 6, wherein said clutch-part has a notch for engaging said continuously reciprocated part, and a foot having a length exceeding the stroke of said continuously reciprocated part away from said notch for holding said clutch-part in its disengaging position, after said electrical means ceases to act, while said notch is out of register with said continuously reciprocated part.

8. Apparatus according to claim 6, wherein said electrical means further comprises an armature, a connection between said armature and clutch-block, and a slot and pin connection between said clutch-block and connection, said slot having a length providing free horizontal movement of said clutch-block throughout the stroke of said continuously reciprocated part.

9. Apparatus for ejecting from a series of blanks being fed to can body making machines and the like, double and overthick blanks, comprising reciprocatory means (A) for feeding blanks in a line, reciprocatory means (B) for feeding a blank laterally from said line to be received by a machine utilizing the blanks, a feeler displaceable by double and overthick blanks fed by means A, said feeding means B comprising a slide, a continuously reciprocated part, a clutch-part on said slide remote from said feeler and movable to and from engagement with said continuously reciprocated part having a notch for engaging said continuously reciprocated part, electrical means operated from said feeler for lifting said clutch-part to a position of disengagement comprising a solenoid, an armature, and a linkage between said armature and clutch-part comprising a slot of a length to provide free horizontal movement of said clutch-part when engaged with and throughout the stroke of said continuously reciprocated part; a fixed shelf beyond said feeding means B for receiving blanks ejected by said feeding means A, and fixed means also beyond said feeding means B for guiding blanks being ejected to a position beneath other blanks stacked on said shelf.
